UNITED STATES PATENT OFFICE.

WILLIAM J. HART, OF MOUNT VERNON, NEW YORK, ASSIGNOR TO SPLITDORF ELECTRICAL COMPANY, OF NEWARK, NEW JERSEY.

COMBINED ENGINE AND DYNAMO-ELECTRIC-MACHINE FRAME.

1,272,949.

Specification of Letters Patent. Patented July 16, 1918.

Application filed December 12, 1916. Serial No. 136,437.

To all whom it may concern:

Be it known that I, WILLIAM J. HART, a citizen of the United States, and a resident of Mount Vernon, in the county of West-
5 chester and State of New York, have invented new and useful Combined Engines and Dynamo-Electric-Machine Frames, of which the following is a clear and exact de-
scription.

- 10 In its broader scope my invention pertains to dynamo electric machines of that class frequently employed to perform various functions in connection with gas engines and other prime movers. In a great many
15 power installations and especially those in which an internal combustion engine is the prime mover, the results afforded by the co-operation of certain types of electrical machines are of such an advantageous nature
20 and secure to the entire system an efficiency and satisfaction of operation that render their use but little short of indispensable. A striking example is the power systems in automobiles and similar autovehicles, in
25 which an internal combustion engine is used as a means to propel the vehicle, and wherein dynamo electric machines are advantageously employed to coöperate with said engine for the purpose of starting, lighting,
30 charging and whatever other such function that may be required. More specifically then, my invention has reference to these power installations for autovehicles wherein dynamo electric machines are coöperatively
35 associated with the prime mover for the performance of such functions as above enumerated, and it especially pertains to certain novel features in the relative construction and arrangement of these elements.
40 One of the chief objects is to provide an installation of the above character such that certain structural parts of these dynamo electric machines are brought into a closer and more intimate relationship with the en-
45 gine than has heretofore been the practice. In the attainment of this purpose I have ar-
ranged so that the field frames of any suit-
able number of electric machines are formed as an integral part of the engine itself, and
50 inasmuch as said machines are adapted to the performance of various duties, their lo-
cation relative to certain operative elements of the engine may be properly selected in order to render them in a position best suited

to the achievement of the various functions 55 for which they are intended.

Another feature to be derived from this invention is the relatively low cost at which an integral construction of this character may be manufactured, and furthermore as-
60 sembly may be more easily accomplished. For instance, by my integral construction I have done away with the necessity of all separate supporting brackets and the like such as are ordinarily used in attaching 65 these auxiliary machines in their working positions.

These and other objects will readily be-
come apparent to those skilled in the art
from the following description taken in con-
junction with the accompanying drawing
which forms a part of this specification, and
wherein—

Figure 1 is a side elevation showing, in a
conventional manner, an internal combustion 75 engine of the four cylinder type, illustrating
the manner and relative position in which I
have associated therewith a motor and a gen-
erator.

Fig. 2 is a left hand end sectional view of 80 Fig. 1. It will be noted that both motor and generator are shown in section and accord-
ingly this view is taken partly on the line
 $x-x$ and partly on the line $y-y$ of Fig. 1.

Referring now in particular to the draw-
ings, wherein like characters of reference
are used to designate like parts in each of
the views, 1 represents generally the casing
of an internal combustion engine such as
commonly used in automobiles and the like. 85 In the figures this engine is of the 4 cylinder
type, but it is to be understood that the pres-
ent invention is not limited to the exact
style of engine shown, but may be used with
engines having any suitable number of cylin-
ders. Furthermore the showing of such 90 engine is more or less of a conventional man-
ner, certain elements being omitted inas-
much as a complete showing is not necessary
to a clear understanding of my invention.
As is usually the practice the casing 1 serves 95 to form the several cylinders for the engine
and also as a partial inclosure for the crank
shaft and its associated parts. At the bottom
portion of this casing 1 are flanges 2. A second
member 3, of any desirable shape, is adapted 100 to coöperate with the member 1 in order
to form a complete housing for the crank
shaft and its associated parts.

shaft. Said housing member 3 is likewise provided with flanges 4 which fit up against the flanges 2 whereby said member may be secured in place as by means of bolts or other suitable fastening means to provide an oil-tight casing within which said crank shaft is adapted to operate. Within this casing the crank shaft 5 is mounted by means of suitable bearings (not shown) and upon one end of which shaft is attached a flywheel 6. Said shaft is provided with cranks 7, properly spaced thereon and whose number depends upon the number of engine cylinders. To crank shaft 5 is attached, by means of crank bearings 9, a plurality of connecting rods one of which is shown at 8. Connected to each of said rods is a piston 10 whereby the explosive force of the combustible gas in the several cylinders of the engine is transmitted through the agency of the several elements above mentioned and becomes effective in imparting the desired rotary motion to the crank shaft 5. Also within the crank casing is the timer shaft 11 which carries a plurality of cam members one of which is shown at 12. These cams are adapted to coöperate in the well known manner with the valve rods 13 whereby the explosive charges may be properly admitted to the engine cylinders. At 14 there is seen to be a diagrammatic representation of a sparking device, such as an electrical spark plug, whose duty it is to fire the explosive charges thus admitted to the engine cylinder to which it is attached. I will not attempt to give a further and more detailed description of the operation of the engine as the same does not form any part of my invention, and is well understood by those skilled in the art to which it appertains.

Coming now to the gist of the present invention, I have made provision whereby the frame structure of any suitable number of dynamo electric machines may be formed in integral relationship with the casing of the engine itself. In the manufacture of engines it is frequently the custom to cast the cylinders *en bloc* of cast iron, and according to my invention means are provided whereby the field frames of said dynamo electric machines are incorporated in this casting as an integral portion thereof. By thus casting these parts in one structure and in the one process a considerable saving in time and labor may be realized. I have therefore shown in the present embodiment a motor and a generator adapted for such purpose as starting, lighting and charging, and which are integrally associated with the engine in accordance with my invention. The field frames of these machines are represented by the characters 15 and 16 respectively. Since it is often preferable that the starting motor be adapted to apply its turning effort to the flywheel of the engine

for the purpose of starting the same, I have provided to have the field frame 15 of said motor located, as shown, at the rear end of the frame 1 in order that the motor armature shaft 17 may be in its most advantageous position to engage the flywheel 6. One suitable method by which such engagement may be accomplished is the use of the so-called Bendix drive, the driving pinion of which is adapted to automatically engage and coöperate with the teeth 18 on the periphery of flywheel 6. On the other side of the engine and preferably near the front end thereof is the lighting and charging generator which likewise has its field frame 16 cast as an integral part of the engine casing 1. By locating the generator in this position it may be very readily connected with the timing shaft 11, to be driven thereby, as by means of gear, chain, or other suitable driving connections. However, it will be understood, of course, that either the generator or motor may be connected directly to the crank shaft 5, and that furthermore their respective locations relative to the engine frame 1 is not restricted to the exact showing of the present embodiment but may be changed if desired to any suitable location, such as best adapts them to the particular engine with which they are to coöperate. 95

Frames 15 and 16 have integral pole pieces 19 and 20 which may be of any suitable number depending upon the particular design of the machine. In order to obtain a reinforcement for the support of said frames 100 15 and 16 and to avoid the liability of dangerous stresses being set up in casing 1, due to the operation of the dynamo electric machines, as for instance the starting of the engine, I have provided supporting brackets 105 21 and 22. These brackets are in form of flanges as best seen in Fig. 1 and are cast as an integral part of the dynamo machine frame and the engine casing.

From the above description it will be 110 apparent that my invention involves a very desirable and economic means of associating the auxiliary dynamo electric machines with the engines of the power systems of motor vehicles. Among the features which it secures is the economic manner in which a construction of this type may be manufactured. For instance, as described, the field frames of any suitable number of machines, their pole pieces and supporting brackets may all 115 be cast in a single process as an integral part of the engine casing. And when the engine is set up to be machined, any necessary machining may be likewise applied to the frame structures of said dynamo electric machines. In the subsequent assembly of said machines the field coils may be quickly applied in position, the armatures inserted, and the end plates bolted in position on the machined ends of said field frames. 125 130

It will be apparent that I am not restricted to the exact details shown and described as many changes and alterations may be made without departing from the spirit 5 of the present invention. It is believed that all such changes will come within the scope of the appended claims.

Having thus described my invention what I claim is:—

- 10 1. In combination an engine and a plurality of dynamo electric machines, a casing for said engine, a field frame and pole pieces for each of said dynamo electric machines and support brackets for said frames, said 15 casing, frames, pole pieces and brackets all being formed as a single integral unitary structure.
- 20 2. An internal combustion engine and a plurality of dynamo electric machines having in combination, a casing serving to form the cylinders of said engine and also as a housing for the crank shaft thereof, and a field frame for each dynamo electric machine having pole pieces thereon and projecting inwardly therefrom, said field frames being formed integral with the engine casing, and adapted to receive rotating armatures between said pole pieces.
- 25 3. In combination with an automobile engine, an electric motor for the purpose of starting said engine, and an electric generator adapted to be operated by said engine, the field frame and pole pieces of both motor

and generator being cast integral with the casing of said engine.

4. In combination with an automobile engine including a casing therefor, a crank shaft and a flywheel operated by said shaft, an electric motor on one side of said casing adjacent said flywheel for the purpose of 35 starting said engine, and an electric generator on the other side of said casing adapted to be operated by the engine, the field frames of said motor and generator being cast integral with the engine casing.

40 5. A combined engine and dynamo electric machine structure comprising a casing for said engine, and a field frame for said dynamo machine having inwardly projecting pole pieces with a rotating armature 45 therebetween, said casing, frame and pole pieces being formed integral with each other.

6. In combination, an internal combustion engine having a crank case the walls of which are of magnetic material, and a plurality of dynamo electric machines having their field structures of magnetic material, one of said dynamo electric machines acting as a starting motor for said engine and another of the dynamo electric machines acting as a generator for producing electrical current, said field structures being cast integrally with the crank case of said engine.

In witness whereof I affix my signature.

WILLIAM J. HART.
